UNITED STATES PATENT OFFICE.

RANDOLPH CROMPTON AND WILLIAM E. WOODMAN, OF WORCESTER, MASSACHUSETTS; SAID WOODMAN ASSIGNOR TO SAID CROMPTON.

FILLING-FEELER MECHANISM.

Application filed April 17, 1919. Serial No. 290,678.

To all whom it may concern:

Be it known that we, RANDOLPH CROMPTON and WILLIAM E. WOODMAN, both of Worcester, in the county of Worcester and Commonwealth of Massachusetts, both citizens of the United States, have invented a new and useful Improvement in a Filling-Feeler Mechanism, of which the following, together with the accompanying drawings, is a specification.

Our invention relates to filling feeler mechanisms for looms.

One object of our invention is to reorganize the construction of filling feeler mechanisms in order to produce a novel form of mechanism embodying, in a single device, the operating principles heretofore separately employed in mechanisms of this character.

A further object of our invention is to provide a novel form of filling feeler mechanism that is characterized by its extreme simplicity and reliability of operation.

It is well known in the art that the function of filling feeler mechanisms is to actuate loom controlling devices for either stopping the loom or for replenishing the weft of an automatic loom upon the substantial exhaustion of the filling on the bobbin or filling carrier. A usual form of filling feeler mechanism heretofore employed has comprised a filling feeler arranged to have a sweeping feeling movement toward the butt of the filling carrier, whereby the feeler is adapted to follow the unwinding surface of the filling carrier and to actuate the loom controlling devices upon a predetermined exhaustion of the filling on the carrier. Such mechanisms have usually employed some form of latch device interposed between the loom controlling means and the weft hammer, and so connected to the filling feeler mechanism as to cause actuation of the loom controlling devices upon a predetermined amount of swing of the filling feeler. In such devices the filling feeler always has a tendency to swing toward the butt of the filling carrier and thereby actuate the loom controlling devices, and various separate instrumentalities, such as controllers having a caliper action with the shuttle, have been employed to prevent this swinging movement of the feeler until the filling has been exhausted, to a predetermined degree.

While filling feeler devices of this general

character are extremely sensitive and capable of fine adjustment as regards the amount of filling remaining on the filling carrier before the loom controlling devices are operated, nevertheless the necessity of providing separate restraining means for controlling the swinging of the feeler has resulted in complicated mechanisms that must be carefully adjusted and maintained, in order to prevent premature operation of the loom controlling devices.

By our invention we propose to provide a novel form of filling feeler mechanism whose operation depends upon a combined caliper and feeler arresting action between the feeler and the filling, and the shuttle, rather than upon the sweeping movement of the feeler alone, or merely upon an independent caliper action with the shuttle. In addition, the mechanism for operatively connecting the loom controlling devices to its operating member is positively maintained out of engagement with that member until the caliper and arresting action of the mechanism causes the loom controlling devices to be actuated upon a predetermined degree of exhaustion of the filling. Consequently the chances of premature operation of the loom controlling devices are considerably reduced by the absence of any auxiliary controlling devices tending to restrain the normal functions of the feeler.

In the accompanying drawings,

Figure 1 is a plan view of a portion of the left hand end of a loom provided with a filling feeler mechanism embodying my invention.

Figure 2 is a view partially in section and partially in side elevation of the parts shown in Fig. 1.

Figure 3 is an enlarged view of a portion of the parts shown in Fig. 1 showing the action of the feeler mechanism upon a predetermined degree of exhaustion of the filling.

Figure 4 is a detail of a portion of the mechanism.

Figure 5 is a fragmentary view showing a modification of the feeler.

Figure 6 is a sectional view of the parts shown in Fig. 5.

Like reference characters refer to like parts in the different figures.

The loom to which our improved filling feeler mechanism is applied may be of any

usual or preferred construction, and may be either a plain loom or an automatic loom. Referring to the drawings, the loom illustrated is of the automatic weft replenishing type, and comprises a lay 1 suitably supported for oscillatory movement toward and from a breast beam 2. The lay 1 is provided in the usual manner with a shuttle box 3 in which a shuttle 4 is adapted to 10 come to rest, when properly boxed, in position to permit the filling feeler mechanism, to be hereinafter described, to determine the extent to which the filling 5 on the bobbin or filling carrier 6 has been exhausted. A 15 longitudinal slot 7 is provided in the front wall 4^a of the shuttle 4 to permit the filling feeler operation, and a portion of the shuttle box 3 is cut away for the same purpose.

A rocker shaft 8 is journalled in suitable 20 bearings at the front side of the breast beam 2 and is connected to either a stopping mechanism or a weft replenishing mechanism, not shown. An upwardly extending rocker arm 10 is mounted on the shaft 8, and a 25 spring 9 acting on a projection of the arm tends to hold the arm 10 toward the beam 2. A weft hammer 11 is suitably mounted on a pivot 12 on the opposite side of the breast beam 2 from the rocker arm 10 and 30 is adapted to be oscillated back and forth with respect to the rocker arm 10 by means of a suitable cam device in timed relation with the movement of the lay 1. All of the 35 parts above enumerated, together with other loom parts shown, are of the usual construction, and their mode of operation is well known to those skilled in the art, so that they need not be further described.

A balance lever 13 is pivotally mounted 40 on a bracket 14 carried by the breast beam 2 by means of a pivot pin 15. The lever 13 is provided with a slot 16 to permit longitudinal movement thereof with respect to its pivot pin 15. The right hand end portion 45 of the lever 13 is located in a depression or notch 17 provided in the upper end of the rocker arm 10, so that the arm 10 holds the right hand end of the slot 16 against the pin 15. The right hand lever portion is 50 made heavier than the left hand portion and a spring 18 secured to the lower side of the lever and to the bracket 14 further tends to turn it in a clockwise direction about the pin 15. The clockwise movement of the lever 13 about its pivot is limited on the 55 left hand side by a stop 19 carried at the upper arm of a lever 20 that is pivotally mounted on a bracket 21 by means of a pivot pin 22, the axis of which is at right angles 60 to the axis of the pivot pin 15. The lower arm of the lever 20 extends at right angles to its upper arm so that the lever 20 is adapted to transmit motion from one plane 65 to another plane that is at substantially right angles thereto. The left hand side of

the lever 13 is provided with a pointed portion 23, that is normally located above the line of motion of the weft hammer 11, but is adapted to be moved into engagement with a notched projection 24 carried by the 70 weft hammer 11 when the lever 20 is actuated by the filling feeler mechanism which will now be described.

A feeler slide 25 is slidably mounted on a stationary plate 26 carried by the breast beam 2 and is yieldingly held toward the lay 1 by means of a tension spring 27 connected between a projection 26^a of the stationary plate 26 and a projection 28 at the outside end of the slide 25. A threaded sleeve 29 coacting with the projection 28 permits adjustment of the spring 27. A stop 30 carried by the slide 25 coacts with the plate 26 to limit the movement of the slide in the direction of the lay 1. The slide 25 is provided at its inner end with a slot 31 within which a feeler wheel 32 is mounted for rotation about its vertical axis on a shaft 33 located at substantially the end of the slide 25. The feeler wheel 32 is provided with peripheral teeth 34 that are preferably acute angled, like the teeth of a rip saw, with their apexes pointed toward the right or away from the butt 6^a of the filling carrier 6, for a purpose to be hereinafter described.

The feeler wheel 33 is further provided with upwardly extending projections 35 and 36, preferably located at diametrically opposite points but at different radial distances from the shaft 33. A lug 37 on the top of the slide 25 is provided with an adjustable stop 38 that extends in the direction of the projection 35, and adapted to be engaged thereby. The stop 38 is here shown as comprising a member in threaded engagement with the lug 37 and adapted to be locked in position by a nut 39, but it is to be understood that any other form of stop capable of being adjusted with respect to the projection 35 may be employed. The projection 36 is provided with an enlarged head 40 that is adapted to engage the wall 4^a of the shuttle 4 above the slot 7 when the feeler wheel 32 projects into the slot 7 a predetermined amount, as will hereinafter appear.

A modification of the feeler wheel adjustment is shown in Figs. 5 and 6, wherein a wheel 41 is provided with a projection 42, similar to the projection 35, and a projection 43 having a head portion 44 eccentric to the vertical axis thereof. The projection 43 extends through the feeler wheel 41 and is provided at its end with a head 45 for the reception of a suitable tool by means of which the projection 43 may be turned to vary the distance between the eccentric head 44 and the wall 4^a of the shuttle. The projection 43 is shown as being in threaded engage- 120
125
130

ment with the wheel 41 and is provided with a nut 46 for locking it in position, although this is not essential.

A flexible member 47, such as string or cable is connected at one end to the lower arm of the lever 20, as shown at 48, and is connected at its other end to the wheel 32 at the point 49, the wheel preferably being provided with a peripheral groove to receive the flexible member 47. With the parts in the position shown in Fig. 1, the lever 13 tends to hold the lower arm of the lever 20 against a stop 50 provided on the bracket 21, as best shown in Fig. 4. Consequently, the flexible member 47 extends between the lever 20 and the feeler wheel 32 without any tension therein due to the forces acting on the levers 13 and 20. The feeler wheel 32 is thus free to turn slightly on its pivot, and any small movement thereof due to its reciprocation and to the vibration of the loom will not be transmitted to the lever 20. When the wheel is actually turned in a clockwise direction, however, by engagement of the shuttle wall 4^a with the projection 36, the flexible member 47 becomes taut and the movement is transmitted freely, and without lost motion to the lever 20 to actuate the loom controlling devices.

Having described the various parts entering into my invention the operation thereof is as follows: Assume that a shuttle with a filling carrier having a considerable amount of filling thereon occupies the position in the shuttle box shown in Fig. 1. On the forward beat of the lay 1 the filling 5 is engaged by the feeler wheel 32 and the slide 25 is moved forward against the action of the spring 27. As the point of contact between the feeler wheel 32 and the filling 5 lies substantially in the same plane as the longitudinal axis of the slide 25, and the axis of the shaft 33, there is no tendency for the wheel to be turned on its shaft. On the backward beat of the lay 1 the feeler wheel 32 still engages the filling and the wheel remains in its normal position with the projection 35 in engagement with the stop 38, as shown Fig. 1.

As the filling 5 is exhausted from the filling carrier 6 the feeler wheel 32 moves a little further into the slot 7 in the shuttle wall as each successive layer of filling is exhausted, the teeth 34 biting into the filling and arresting any tendency for the wheel to turn in a clockwise direction due to slight variations in the bobbin or filling carrier. When the filling has been exhausted to a predetermined degree, as for example when the filling has been removed from the carrier substantially up to its point of contact with the wheel, as shown in Fig. 3, the projection 36 is engaged by the upper wall 4^a of the shuttle. As this occurs on the forward beat of the lay, the force of

the blow is sufficient to turn the wheel 32 in a clockwise direction on the shaft 33, there then being practically no filling engaged by the teeth 34 which would tend to arrest the turning of the wheel. The turning movement of the wheel is transmitted to the lever 20 through the flexible member 41 which causes the stop 19 to engage the lever 13 and move it downward in a counterclockwise direction into the path of motion of the weft hammer 11, as shown in dotted lines in Fig. 2. The projection 24 of the weft hammer thereupon engages the lever 13 and moves the rocker arm 10 on its shaft 9 to actuate the loom controlling devices.

The degree of exhaustion of the filling 6 on the filling carrier necessary to actuate the loom controlling devices as described above, may be regulated by means of the stop 38. Moving the stop toward the projection 35 holds the projection 38 further away from the wall 4^a of the shuttle, thereby causing the engagement of the shuttle with the projection 36 to occur after more filling has been removed from the filling carrier. Moving the stop 38 in the opposite direction causes the projection 36 to be engaged by the shuttle earlier in its forward beat, thereby increasing the amount of filling that is left on the filling carrier. It has been found that the operation of the filling feeler mechanism can be adjusted with considerable delicacy by varying the position of the stop 38, as described above. For instance, the stop can be set so that the feeler wheel 32 will not be turned until after the projection 36 has been struck several blows by the shuttle wall 4^a, or it can be set so that the feeler wheel is turned by the first blow of the shuttle, the extent of the arresting action caused by the engagement of the feeler teeth with the filling, determining the quickness with which the device operates. In this way the amount of filling remaining upon the filling carriers may be varied. Other adjustments can be made at the stop 19 and at the sleeve 29 in order to properly regulate the operation of the mechanism.

From the foregoing it is apparent that, viewed in its broader aspects, our invention is not limited to the specific form of filling feeler mechanism shown herein, or to the specific arrangement of the parts of the loom controlling devices shown in relation to the filling feeler mechanism. The invention is broad in scope and in character, for it is the first filling feeler mechanism to employ a toothed and freely rotatable feeling member so mounted as to have a combined feeler arresting and caliper action with the filling and the shuttle, independent of any external controlling or restraining devices. It therefore represents a distinct and important advance in the art, for by its use it is possible to construct an extremely sim-

ple and reliable filling feeler mechanism that combines all of the advantageous features of the mechanisms heretofore constructed. We desire, therefore, that only such limitations be placed thereon as come within the scope of the appended claims.

We claim:

1. In a filling feeler mechanism for looms, a feeler member rotatably mounted about a vertical axis and provided with a toothed filling engaging portion concentric about said axis, and a projecting shuttle engaging portion located eccentrically with respect to said axis.
2. In a filling feeler mechanism for looms, a feeler member rotatably mounted about a vertical axis and provided with filling engaging teeth at equal radial distances from said axis, and a shuttle engaging projection located nearer to said axis than said teeth.
3. In a filling feeler mechanism for looms, a rotatably mounted disk provided around its periphery with filling engaging teeth and having a shuttle engaging abutment projecting from the surface thereof.
4. In a filling feeler mechanism for looms, a rotatably mounted wheel provided around its periphery with filling engaging teeth and having a shuttle engaging projection located eccentrically with respect to the axis of rotation of said wheel.
5. In a filling feeler mechanism for looms, the combination with a shuttle, a filling carrier and a slide movable in the direction of the shuttle, of a feeler member rotatably mounted on the slide and provided with teeth and with a projection for engagement with the filling and the shuttle respectively.
6. In a filling feeler mechanism for looms, the combination with a shuttle, a filling carrier and a slide movable in the direction of the shuttle, of a feeler member rotatably mounted on the slide and provided with filling engaging teeth and with a projection adapted to be engaged by the shuttle to cause rotation of said member upon substantial exhaustion of the filling.
7. In a filling feeler mechanism for looms, the combination with a shuttle, a filling carrier and a slide movable in the direction of the shuttle, of a feeler member rotatably mounted on the slide and provided with filling engaging teeth and with a shuttle engaging projection located eccentrically with

respect to the axis of rotation of said member.

8. In a filling feeler mechanism for looms, the combination with a shuttle, and a filling carrier with filling thereon, of a toothed filling engaging member mounted for free rotational movement and provided with a projection, rotational movement being imparted to said member by the engagement of said projection with the shuttle.

9. In a filling feeler mechanism for looms, the combination with a shuttle, a filling carrier and filling thereon, of a toothed filling engaging member mounted for reciprocatory and free rotational movement, the rotational movement being imparted to said member by the engagement of said shuttle with an integral portion thereof.

10. In a filling feeler mechanism for looms, a toothed filling engaging wheel mounted for reciprocatory movement in a straight line at right angles to the line of movement of the loom shuttle and for rotative movement about a vertical axis passing through the said line of reciprocatory movement, the said wheel being free to rotate when not in engagement with the filling, and its rotative movement being subject only to the arresting action between the teeth and the filling at the point of tangency of the wheel to the filling.

11. In a loom, the combination with loom controlling devices and a rotatably and slidably mounted filling feeler capable of free rotational movement independent of its sliding movement, of a normally slack flexible member operatively connecting said feeler to said loom controlling devices.

12. In a loom, the combination with loom controlling devices and a rotatably and slidably mounted filling feeler capable of rotational movement independent of its sliding movement, of a flexible member directly connecting said feeler to said loom controlling devices, whereby slight rotative movement of said feeler is permitted without actuating said loom controlling devices.
